CLAIM

The ornamental design for a cooking appliance as shown and described.

DESCRIPTION

FIG. 1 is a perspective view of the cooking appliance;

FIG. 2 is a front view thereof;

FIG. 3 is a rear view thereof;

FIG. 4 is a right side view thereof;

FIG. 5 is a left side view thereof;

FIG. 6 is a top view of thereof;

FIG. 7 is a bottom view thereof; and,

FIG. 8 is an enlarged cross-sectional view taken along line 8-8 in FIG. 2.

The dashed broken lines show portions of the cooking appliance and form no part of the claimed design. The dash-dot broken lines depict the bounds of the claimed design and form no part of the claimed design.

1 Claim, 6 Drawing Sheets
